(Cl. D74—1)

To all whom it may concern:

Be it known that I, Leigh S. Taylor, a citizen of the United States, residing at Dallas, in the county of Dallas and State of Texas, have invented a new, original, and ornamental Design for a Continuous Memorandum Device or Similar Article, of which the following is a specification, reference being had to the accompanying drawing, forming part thereof.

Figure 1 is a front elevational view.

Figure 2 is a side elevational view, and

Figure 3 is a rear elevational view of a continuous memorandum device or similar article, showing my new design.

I claim:

The ornamental design for a continuous memorandum device or similar article, substantially as shown.

LEIGH S. TAYLOR.
